LAVATORY

Gerard D. Phillips, Jr., Louisville, Ky., assignor to American Radiator & Standard Sanitary Corporation, New York, N.Y., a corporation of Delaware

Filed Dec. 8, 1960, Ser. No. 63,155

Term of patent 14 years

(Cl. D4—2)

FIGURE 1 is a view, in perspective, of a lavatory showing my new design;

FIGURE 2 is a top, plan view thereof;

FIGURE 3 is a front view, in partial cross-section on line 3—3 of FIG. 2 and looking in the direction of arrows 3—3;

FIGURE 4 is a view in section on the line 4—4 of FIG. 2; and

FIGURE 5 is a view in side elevation looking from left to right of FIG. 2.

The back of the lavatory is substantially plain.

I claim:

The ornamental design for a lavatory, substantially as shown and described.
